HERMANN LAUR, OF KEHL, GERMANY

LINKS FOR SERIAL LAMP SUPPORTS

Application filed March 29, 1930, Serial No. 440,120, and in Germany May 5, 1929.

The present invention relates to a lighting chain consisting of joined links and serving as lamp support for advertising, decorative or similar purposes, the links being made 5 from pressed insulating material and containing the conductors while the lamp socket is arranged in the axis of rotation.

Compared with existing arrangements of this sort the chain according to the invention 10 is superior for the reason that the lamp sockets establish both the mechanical and the electrical connection between two chain links so that it becomes possible to produce chains of any desired length on the spot simply by combining the links and inserting the 15 lamps in their common pivots without requiring special auxiliary means. Moreover, various effects may be produced by the combination and arrangements of the chains so 20 obtained.

One form of the invention is illustrated in the accompanying drawings, in which Figure 1 is a longitudinal section of a chain link; Fig. 2, a top view thereof; Fig. 3, a longitudinal section of a chain consisting of three 25 links with lamps inserted therein; and Fig. 4, a view of an illuminated letter produced by means of a chain according to the invention.

30 Referring to the drawings, the link made from pressed insulating material possesses a body 1 forming on one end the fork 2 and on the other a projection 3 fitting between the ends of the fork of an adjoining link.

35 The upper end of the fork is perforated to receive the lamp socket which is passed through it, and the lower fork end has a cuplike indentation 4 wherein ends a contact blade 5 embedded in the body of the link. 40 The other end of the blade is connected to a metallic female thread 6 inserted in the projection 3.

45 The body 1 contains also a plug socket 7 extending transversely to the contact blade and coming in touch therewith and a terminal screw 8 leading to the contact blade. In said socket the terminal plugs of an electric supply wire may be inserted and fastened by means of the screw 8. When two links are 50 to be assembled, the projection 3 of one link

is inserted between the forked ends of the other, whereupon the socket 9 of the lamp 10 is screwed in so that it passes through the bore of the upper forked end and the female screw 6 of the projection 3 and with its center contact rests in the indentation on the elastic end of the contact blade 5.

55 Attachment to the base takes place by means of clips secured by screws or nails as in case of electric conduits.

I claim:—

60 In a lighting chain comprising links serving as lamp supports and as means for connecting the lamps in series, each link comprising an elongated body portion of insulating material, said body portion being forked at one end and having a reduced extension at the other end, the reduced extension of one link fitting between the forked parts of an adjacent link; the extension and one of the 65 forked parts being perforated, the other forked part having a recess; and an electrical conductor extending from the bottom of said recess to the perforation in the extension and forming a conducting wall for said 70 perforation.

HERMANN LAUR.
